SELF-ALIGNING CARRIER

Robert G. Le Tourneau, Longview, Tex., assignor
to R. G. Le Tourneau, Inc., Peoria, Ill., a corporation of California

Application July 18, 1950, Serial No. 174,450

7 Claims. (Cl. 198—202)

This invention relates to belt type carriers or conveyors and more particularly to such a carrier that is conveyed over rolls.

It is extremely difficult to keep carriers of any length in the proper alignment on their rolls and some type of adjusting means is usually required for satisfactory operation. This is especially true where the belt travels at a high speed such as in earth loading machines. The tendency in these operations is for the belt to creep to one side or the other of the roll and if not corrected, the belt could work completely off the rolls, or damage itself on adjacent equipment.

It is therefore the primary object of this invention to provide a mechanism for automatically aligning a carrier belt on its rolls at the first indication that the belt is riding to one side.

Another object of this invention is to provide a means for preventing the alignment mechanism from sending the belt too far in the other direction when making the adjustment.

A further object of this invention is to provide an electrically actuated linkage which will move the troughing roll in one direction and the carrier roll in the other direction to better align the belt which is traveling in opposite directions over each.

These and other objects will be apparent from a perusal of the following specification and drawings in which:

Fig. 1 represents a plan view of the carrier with a portion of the belt cutaway to show the alignment mechanism of this invention. The troughing rolls and one roller 8 and associated parts have been omitted from this view for clarity of illustration.

Fig. 2 is an elevational view of the mechanism including the troughing and carrier rolls taken in section along lines 2—2 of Fig. 1.

Fig. 3 is a section taken along the lines 3—3 of Fig. 1.

Fig. 4 is a side elevational view of the carrier showing the relationship of the various rolls thereof.

Referring now more particularly to the drawings, a carrier containing the instant invention is seen to consist of a frame 1 including side arms 2 and 2a spaced apart by means of cross members 3. Troughing rolls 4 are journaled in cross members 3, on the top of which rolls an endless belt 5 rides. The self-aligning troughing rolls 4a are journaled in a pivoted cross member 3a, and directly beneath a carrier roll 6 is journaled in a second pivoted cross member 7.

The belt 5 travels up the incline (as shown in

Fig. 1) and over a power driven head pulley H and then reversing its direction, travels over snubbing roll R and through a floating snubber structure S, and at the lower end of the carrier, the belt passes around direction changing pulley D to complete its cycle.

Near the top of the carrier frame 1 a guide roller 8 is journaled as at 9 in a bracket 10 which is pivoted, as a unit, to mount 11 by pin 12. This bracket 10 is free to pivot about pin 12 under the urging of belt 5 until it strikes bolt 13 of stop bracket 14. However just prior to engagement with bolt 13 the bracket 10 by means of attached pad 15 will depress plunger 16 of a normally off switch 17 attached to frame 1. This switch 17 will actuate a small reversible motor 18 which will through its pinion 19 cause gear 20 and attached lead screw 21 to rotate. Lead screw 21 includes threads 22 which cooperate with threads 23 of sleeve 24 to cause sleeve 24 to advance or retract according to the direction of rotation of motor 18. Sleeve 24 is pivoted by means of pin 25 to pivot bar 26. Motor 18 and attached gear housing bracket 28 are pivoted by means of pin 27 and bracket 29 on frame 1 so that it may follow the lateral movement of pin 25 which naturally occurs when pivot bar 26 is rotated about its pivot pin 30. Link arms 31 and 31a are threaded at each end as at 32 to engage threaded lugs 33 at their pivot bar end and threaded lugs 34 at their other ends. These lugs provide pivotal connections to pivot bar 26 and cross members 3a and 7 respectively by means of pins and stud 36.

It will be observed that when belt 5 attempts to override rolls 4 to the left (toward side arm 2) it will force roller 8 and bracket 10 laterally outward against the tension of spring 37 until bracket 10 depresses plunger 16 of switch 17. Spring 37 is normally under tension to keep bracket 10 snug against stop piece 38 welded to frame 1 at 38a; it is attached between stop piece 38 and a projecting lug 39 of bracket 10. This switch will cause motor 18 to rotate in such a direction to force the adjacent end 40 of bar 26 away from motor 18 and since bar 26 pivots about its pin 30 this action will cause link 31 and consequently cross member 7 to move away from motor 18 and in this direction belt 5 will be forced toward side arm 2a due to the changed alignment of roll 6. At the same instant link 31a will be moved toward motor 18 under the action of end 40a of bar 26 to cause top cross member 3a and troughing rolls 4a to be out of lateral alignment in an opposite direction from member 7 and thereby contribute to moving belt 5 in a di-

rection away from roller 8 and toward side arm 2a. Belt 5 under the influence of members 7 and 3a and their respective rolls 6 and 4a will gradually move away from roller 8, and will continue until roll 6 has moved to a set angle, at which time an extension 41 of cross member 7 will strike against cut off switch 42a mounted on side arm 2. Switch 42a stops the flow of electric current to motor 18 for any further rotation in the direction in which it has been operating. Belt 5 may, however, continue its gradual movement toward the roller of bracket 10a on the opposite side arm 2a. When this happens, a switch 17a on this side will operate in the same manner as before except here it will cause the direction of rotation of motor 18 to reverse and consequently gradually reverse the positions of members 7 and 3a until they have moved sufficiently to permit extension 41 to strike against a second cut off switch 42 and again stop motor 13 from further rotation in that direction.

In examining structural details it will be seen that roll 6 is journalled in end pieces 43 depending from cross member 7 at the extreme ends thereof, while troughing rolls 4a are journalled as in the end pieces 44 of member 3a as well as intermediate pieces 45 and these rolls 4a are interaligned in a conventional troughing arrangement. Cross members 3a and 7 are supported in space by means of a turntable structure 46 which includes cross struts 47 fastened between side arms 2 and 2a of frame 1. Plate 48 of turntable 46 fits snugly but in sliding relation between bottom plate 49 of cross member 3a and top plate 50 of cross member 7. A depending stud 51 is welded to channel 52 and plate 49 of top cross member 3a and this stud has a nut 53 locked thereto on its threaded end by means of set screw 54. The relationship of parts here is such that top member 3a and stud 51 may turn in central opening 55 of turntable 46, and bottom cross member 7 may turn about stud 51 and on nut 53.

A lubrication fitting 56 is threaded into plate 49 to permit insertion of lubricant for plates 49 and 50 to provide for easy turning between these plates and turntable 48. This lubricant will also find its way through openings 55 and 57 into pocket 58 of nut 53 so that the sliding contact between cross member 7 and nut 53 may be lubricated.

From the foregoing description it will be readily seen that there has been produced such a device as substantially fulfills the objects of the invention as set forth herein.

While this specification sets forth in detail the present and preferred construction of this invention, still in practice such deviations from such detail may be resorted to as do not form a departure from the spirit of the invention, as defined in the appended claims.

Having thus described my invention, what is claimed as new and useful and is desired to be secured by Letters Patent is:

1. A self-aligning carrier comprising spaced rolls including a troughing roll and a carrier roll, a continuous conveyor belt riding over said troughing roll in one direction and over said carrier roll in the opposite direction; said troughing roll and said carrier roll being pivoted for belt adjusting movement, a link associated with each roll, a pivot bar connected near each end to one said link, the pivot for said pivot bar being intermediate said end connections, an electric power unit operatively connected to one end

of said pivot bar so that operation of said electric power unit will cause said links to move in opposite directions thereby causing said troughing roll and said carrier roll to pivot in opposite directions and cause movement of the conveyor belt axially of said rolls; a normally-off switch associated with the edge of said conveyor belt and operative to start said electric power unit when said conveyor belt creeps out of alignment with said spaced rolls.

2. A self-aligning carrier comprising spaced rolls including a troughing roll and a carrier roll, a continuous conveyor belt riding over said troughing roll in one direction and over said carrier roll in the opposite direction; said troughing roll and said carrier roll being pivoted for belt adjusting movement, a link associated with each roll, a pivot bar connected near each end to one said link, the pivot for said pivot bar being intermediate said end connections, an electric power unit operatively connected to one end of said pivot bar so that operation of said electric power unit will cause said links to move in opposite directions thereby causing said troughing roll and said carrier roll to pivot in opposite directions and cause movement of the conveyor belt axially of said rolls; a normally-off switch associated with the edge of said conveyor belt and operative to start electric power unit when said conveyor belt creeps out of alignment with said spaced rolls, a limit switch associated with said carrier roll and operative to shut off said electric power unit when said roll has pivoted through a predetermined angle.

3. A structure for a self-aligning carrier comprising a frame, side walls on the frame, cross members connecting to said side walls in rigid relation, one cross member including spaced struts, a center plate connected between said struts, a central opening in said plate, a troughing roll bracket including a bottom plate and a depending stud resting on said center plate, a troughing roll on said bracket, a carrier roll bracket including a top plate with a central opening abutting said center plate, a carrier roll on said carrier roll bracket, said stud projecting through the central openings in said center plate and said top plate and having a nut locked on the free end thereof whereby to permit said troughing roll bracket and said carrier roll bracket to pivot about the axis of said stud; a continuous conveyor belt having one flight carried by said troughing roll and the other by said carrier roll; a motor unit including a lead screw pivoted to said frame, a pivot bar pivoted to said frame intermediate the length of the bar, a threaded sleeve pivoted to one end of said pivot bar, said lead screw engaging said sleeve in actuating relation; a link connected at each end of said pivot bar at their one end, one of said links pivotally connected at its other end to said troughing roll bracket, the other link being pivotally connected to said carrier roll bracket; the motor unit, pivot bar, links, and brackets being so connected that operation of the power unit will cause the troughing roll bracket to move in one direction about the axis of its stud and yet cause the carrier roll bracket to move in the opposite direction about the axis of said stud at virtually the same rate of speed, and a switch engageable by said belt to actuate said motor unit.

4. A structure for a self-aligning carrier comprising a frame, side walls on the frame, rolls mounted in said frame, a conveyor belt riding

on said rolls in longitudinal alignment, cross members connecting to said side walls in rigid relation, one cross member including spaced struts, a center plate connected between said struts, a central opening in said plate, a troughing roll bracket including a bottom plate and a depending stud resting on said center plate, a troughing roll in said troughing roll bracket, a carrier roll bracket including a top plate with a central opening abutting said center plate, a carrier roll in said carrier roll bracket, said stud projecting through the central openings in said center plate and said top plate and having a nut locked on the free end thereof whereby to permit said troughing roll bracket and said carrier roll bracket to pivot about the axis of said stud; spaced rolls supported by said frame, an electric motor unit including a lead screw pivoted to said frame, a pivot bar pivoted to said frame intermediate the length of the bar, a threaded sleeve pivoted to one end of said pivot bar, said lead screw engaging said sleeve in actuating relation; links connected at each end of said pivot bar at their one end, one of said links pivotally connected at its other end to said troughing roll bracket, the other link being pivotally connected to said carrier roll bracket; the electric motor unit, pivot bar, links, and brackets being so connected that operation of the power unit will cause the troughing roll bracket to move in one direction about the axis of its stud and yet cause the carrier roll bracket to move in the opposite direction about the axis of said stud at virtually the same rate of speed; a bracket pivoted to said side arm and a belt guide roller journaled in said bracket, said roller and bracket moving outward under the pressure of said belt when said belt creeps out of longitudinal alignment with said spaced rolls to engage and close a switch to actuate said motor unit.

5. A conveyor comprising a frame; troughing rolls; carrier rolls; a continuous belt having its upper flight carried by said troughing rolls and its lower flight carried by said carrier rolls; means mounting at least one set of troughing rolls for pivotal movement about an axis perpendicular to said belt; means mounting a corresponding carrier roll for pivotal movement about an axis perpendicular to said belt; an electric motor operatively connected to said mounting means and adapted when actuated to pivot said set of mounting rolls in one direction and said corresponding carrier roll in the opposite direction about said axes; a switch mounted adjacent one side of one flight of said belt and adapted to be closed upon contact with said belt to actuate said motor and pivot said set of troughing rolls and said corresponding carrier roll to positions to cause said flights of said belt to travel in a direction away from said switch.

6. A conveyor comprising a frame; troughing rolls; carrier rolls; a continuous belt having its upper flight carried by said troughing rolls and its lower flight carried by said carrier rolls; means mounting at least one set of troughing rolls for pivotal movement about an axis perpendicular to said belt; means mounting a corresponding carrier roll for pivotal movement about an axis perpendicular to said belt; an electric motor operatively connected to said mounting means and adapted when actuated to pivot said set of mounting rolls in one direction and said corresponding carrier roll in the opposite direction about said axes; a switch mounted adjacent one side of one flight of said belt and adapted to be closed upon contact with said belt to actuate said motor and pivot said set of troughing rolls and said corresponding carrier roll to positions to cause said flights of said belt to travel in a direction away from said switch; a limit switch adapted to be engaged upon pivotal movement of said pivotally mounted rolls and prevent further pivotal movement thereof; a second switch mounted adjacent the other side of said one flight of said belt and adapted when contacted by said belt to close and actuate said motor in reverse direction to pivot said set of troughing rolls and said corresponding carrier in directions opposite to that caused by closing of said first switch.
7. A conveyor comprising a frame; troughing rolls; a carrier roll; a belt adapted for movement over the troughing rolls and the carrier roll, the direction of movement over the troughing rolls being opposite from that over the carrier roll; means mounting the troughing rolls in said frame for pivotal movement about an axis perpendicular to said belt; means mounting the carrier roll in said frame for pivotal movement about an axis perpendicular to said belt; and means responsive to lateral movement of the belt for causing pivotal movement of the troughing rolls in one direction about said axis while simultaneously causing pivotal movement of the carrier roll in the other direction.

R. G. LE TOURNEAU.
